UNITED STATES PATENT OFFICE.

SAMUEL G. McFARLAND, OF NEW YORK, N. Y.

FLUSHING APPARATUS FOR WATER-CLOSETS.

SPECIFICATION forming part of Letters Patent No. 378,100, dated February 21, 1868.

Application filed January 25, 1866. Serial No. 189,581. (No model.)

To all whom it may concern:

Be it known that I, SAMUEL G. McFARLAND, of the city and State of New York, have invented an Improvement in Flushing Apparatus for Water-Closets, of which the following is a specification.

The object of this invention is to create a suction between the two traps of the water-closet sufficient to produce a siphoning action that discharges the contents of the closet-basin. To effect this object the entire flushing-cistern is inclosed, so that the descent of the water therein when it flows to the closet-basin produces a suction in a pipe leading from the siphon of the traps up into the flushing-cistern.

In the drawing I have represented my improvement by a vertical section, showing the closet and the flushing-cistern.

The flushing-cistern A is of any desired size or shape, and the water is to be supplied into the same by a ball-valve or other convenient mechanism. B is the pipe leading from the flushing-cistern to the rim C of the water-closet bowl D, and within the flushing-cistern A is a siphon-pipe, E, with a valve, F, at its lower end, and this pipe and valve are lifted by a rod, G, and any suitable connection to the pull of the water-closet. The parts thus far named are of any ordinary character, except that the flushing-cistern is closed on the top by a plate or plates, H, that is air-tight, or nearly so, and in the same is a hole through which the rod G passes. There may be a packing around this rod G; but ordinarily it is sufficient to make the hole but slightly larger than the rod.

At the back of the water-closet bowl D is the vertical dam T, and a siphon-discharge, K, leading down to the lower trap, L, that intervenes between the siphon and the sewer-pipe M, and the partition P, between the siphon and the bowl D, is convex at the side next the bowl D, as shown in the drawing, the object of this convexity being to throw the water that issues from the flushing-rim C at the back of the closet sufficiently away from the discharge-opening between the basin and the siphon to fall upon and submerge any paper that may be partially floating in the water of the basin, and thereby compel the discharge of the paper with the rest of the contents of the basin through the siphon and trap, as hereinafter stated.

From the upper part of the siphon K a pipe, S, passes up into the flushing-cistern, the upper end being near the under side of the cover H.

The operation is as follows: The flushing-cistern being filled, as usual, up to near the overflow, the pipe E and valve F are raised by the rod G and closet-pull, and the water of the flushing-cistern rushes rapidly down the pipe B into the bowl of the closet through the flushing-rim C, and the water overflows the vertical dam T in the siphon K, and the descent of the water in the cistern A produces minus pressure of atmosphere in the upper part of said cistern and draws the air out of the siphon K through the pipe S, so that this siphon fills with water, and the column of water in said siphon K, the trap L, and sewer-pipe M causes a powerful current that draws the water out of the bowl D and discharges the contents thereof, and any paper which might otherwise float in the bowl is submerged and carried away with the water, as aforesaid. The rapidity of discharge causes the level of the water in the bowl D to descend so rapidly that air is drawn into the siphon K and the same ceases to act, and air rushes up into the cistern to supply the minus pressure therein. The water runs from the cock Q to refill the cistern, and I provide a small pipe, R, opening at its lower end below the valve-seat into the pipe B, and the upper end is in the discharge-opening of the cock, so that a portion of the water discharged by said cock passes into the said pipe R and runs into the closet during the time that the water is running into the cistern, so as to fill the bowl up to the top of the dam T.

The hand-hole and cover at U serve to give access to the trap L in case the same becomes obstructed.

I do not claim a water-closet cistern in which there is a flushing-chamber closed at the top and provided with an air-valve and with a valve to admit water into the flushing-chamber, and a flushing-pipe and valve leading to the closet, and an air-pipe from the trap of the closet up into the flushing-chamber; neither do I claim a closet-basin having inclined concavo-convex sides over which the water flows and in which the action of the water is nearly uniform all around the basin. By my improvement the water acts above the trap to submerge

paper or other floating substances, and at all other portions of the basin to drive the contents of the basin toward the discharge-opening.

I do not herein lay claim to the water-closet 5 basin, as a basin of the particular form shown is not necessarily employed with my improved cistern, and I do not abandon any legal rights I may have in the premises.

I claim as my invention—

10 The water-closet cistern having a closed top, in combination with the water-supply cock and float within the cistern, a pipe, S, opening near the under side of the cistern-cover and passing to the siphon of the closet, the flushing-pipe

B, leading to the rim of the closet, a valve at 15 the upper end of such pipe, a siphon-tube connected with the valve, and a rod passing through the cover of the cistern and connected to the siphon and valve for lifting the same when the closet - pull is operated, substantially as set 20 forth.

Signed by me this 21st day of January, A. D. 1886.

SAMUEL G. McFARLAND.
